United States Patent Office

Des. 188,686
Patented Aug. 23, 1960

188,686

UTENSIL HANDLE

Mark K. Maynard, 1444 E. Colorado Blvd.,
Glendale, Calif.

Filed Oct. 3, 1958, Ser. No. 52,860

Term of patent 14 years

(Cl. D44—29)

Fig. 1 is a perspective view of a utensil handle illustrating this invention, showing a serving spoon in phantom lines assembled in the handle for purposes of illustration only;

Fig. 2 is a plan view of the front face of the handle shown in Fig. 1;

Fig. 3 is a plan view of the back face of the handle shown in Figs. 1 and 2;

Fig. 4 is a side view of the handle shown in the preceding figures;

Fig. 5 is an end view of the handle shown in the preceding figures, as viewed from the utensil end thereof, and

Fig. 6 is an end view of the handle shown in the preceding figures, viewed from the exterior end thereof.

I claim:

The ornamental design for a utensil handle, as shown and described.
